UNITED STATES PATENT OFFICE.

FRANK L. GORMLEY, OF BROOKLINE, MASSACHUSETTS, ASSIGNOR TO THE BUDA COMPANY, OF HARVEY, ILLINOIS, A CORPORATION.

HIGH-SPEED SELF-LOWERING LIFTING JACK.

Application filed December 21, 1926. Serial No. 156,111.

This invention relates to lifting jacks and particularly to that class known as self-lowering jacks in which a steep pitch rotatable screw is used to raise the ram in its supporting standard.

The object of the invention is the production of a jack of this character which is capable of supporting the heaviest loads and which may be locked to sustain the load at a given height; which may be lowered by manually withdrawing a key from a vertical groove in the ram, said key automatically returning into said groove when released to prevent further lowering; which will provide an inner bearing for the driving shaft thereby maintaining the screw gear and its driving gear in proper relation to each other; which is provided with means for determining the exact amount the load has been raised; which may be operated by the lifting lever in one direction only and that is in raising the ram; which may be operated in either direction by hand to raise or lower the ram; and which is provided with novel means for locking the lifting lever handle in the socket of the operating mechanism for imparting movement to the driving gear.

This object and other desired results are attained by the mechanism shown in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings—

Figure 1 represents a vertical section of a lifting jack embodying the principles of the present invention.

Figure 2 represents an elevation of the upper end thereof with the ram raiser in its supporting casing.

Figure 3 represents a vertical section of the automatic locking device.

Figure 4 represents a vertical section on line 4, 4, on Figs. 1 and 5.

Figure 5 represents a vertical section on line 5, 5, on Fig. 4.

Figure 6 represents a horizontal section on line 6, 6, on Fig. 5.

Figure 7 represents a vertical section of the clutch mechanism on line 7, 7, on Fig. 4.

Figure 8 represents a vertical section on line 8, 8, on Fig. 1.

Figure 9 represents a side elevation of the end of the handle of lifting lever.

Figure 10 represents an end elevation of said handle, and

Fig. 11 represents a sectional view of certain details.

Similar characters indicate like parts throughout the several figures of the drawings.

The present invention is an improvement on the lifting jacks shown and described in Letters Patents of the United States, numbered 1,570,962 and 1,574,476, issued to me respectively January 26, 1926, and February 23, 1926.

In the drawings, 10 is the base of a lifting jack having an upwardly extending projection 11, to which is threaded the lower end of a standard 12, in the upper end of which is a cylindrical bearing 13 for the vertically movable ram 14.

This ram 14 has an enlarged head 15 adapted to rest upon the upper end of the standard 12 when in its lowest position.

The lower end of the ram 14 has mounted therein a nut 16 threaded to the main lifting screw 17, the lower end of which has keyed thereto a bevel gear 18 meshing with a bevel gear 19 formed upon the actuating shaft 20.

The shaft 20 has mounted on its outer end a device 21 for imparting rotary movement to the shaft 20 in one direction only, and that is, during the lifting operation.

The standard 12 has a lateral extension 22, one vertical wall of which has a bearing 23 therein, in which said actuating shaft 20 is mounted.

In the chamber formed by this lateral extension 22 is mounted a worm gear 24 secured to the actuating shaft 20 and meshing with a worm 25 formed upon the horizontal shaft 26.

The pitch of the thread of said worm 25 is such as to permit it to be rotated by said worm gear 24 in whichever direction the gear 24 may be rotated.

Surrounding the hub of the gear 18 is a bearing plate 27 having a groove in its under face into which extend the anti-frictional

members 28 resting upon another bearing plate 29 supported and centrally disposed within the depression 10* in the upper face of the base 10.

5 One end of the worm shaft 26 is mounted in a bearing in the wall of the extension 22, while the opposite end is mounted in a bearing in a removable member 30, set into the opposite wall of said extension.

10 Roller bearings 31 and 32 are provided at the opposite ends of the worm shaft 26.

Keyed to the shaft 26 is an annular member 33 having loosely mounted thereon a worm gear 34 provided with an annular flange 35 15 having secured therein a ratchet 36.

The member 33 has a flange 37 at one end thereof on which is pivotally mounted a plurality of pawls 38, normally forced outwardly by springs 39 into engagement with the teeth 20 of the ratchet 36.

The worm gear 34 coacts with a vertical worm 39* formed upon the shaft 40.

This shaft 40 has a bearing 41 in the lower wall of the extension 22 and another bearing 25 42 in the partition or wall 43 near the upper end of said extension.

Between the under face of the extension 43 and the shoulder 44 on the worm 39* is a thrust bearing 45.

30 The upper end of the shaft 40 has keyed thereto a disk 46 having pivotally mounted thereon at 47 a plurality of bearing plates 48, adapted to move outwardly against the brake arms 50 surrounding the disk 46 and bearing plates 48, said brake arms 50 being pivoted at one end at 51 to the wall 43.

The opposite ends of the brake arms 50 are provided with parallel, separated extensions 52, between which is positioned a cam 40 member 53 mounted upon a pin 54 extending upwardly through the cover plate 55 and having an actuating finger 56 secured to its upper end.

45 Springs 58 normally retain the brake arms 50 in contact with the bearing plates 48 pivotally mounted upon the disk 46.

When the parts are in the position indicated in the drawings there will be sufficient friction between the brake arms 50 and the bearing plates 48 to retain the ram in elevated 50 position and prevent its lowering under the load.

When it is desired to lower the load the operator manipulates the finger 56 causing 55 the cam 53 to separate the brake arms 50, thereby reducing the frictional contact between these arms and the bearing plates 48.

It is obvious that by the movement of the finger 56 about the axis of the pin 54 any degree 60 of friction between the arms 50 and plates 48 may be secured and the speed of lowering the ram controlled.

The extension 22 is formed integral with the standard 12 and the partition or wall 65 43 is formed integral with the removable

member 30, this wall being somewhat depressed and forming a chamber 59 in which the speed controlling devices 46, 48, 50, and 53, are positioned, this chamber being closed by means of the cover plate 55.

The bearing 23 is provided with a bushing 60 and the shaft 20 may be installed in the bearing 23 from the inner end thereof before the bushing 60 is inserted into the outer end thereof, the said shaft being inserted into the chamber within the extension 22 through the opening in the bottom of the standard 12 before said standard has been threaded to the base 10.

70 The bushing is then positioned within the bearing 23 and around the shaft 20 and then the casing 21 of the actuating device is installed on the outer end of said shaft.

The worm gear 24 and the worm 25 rotate both when the ram is being raised and also 75 when it is being lowered.

When the load is being lifted the worm 39* and worm gear 34 are prevented from being rotated by means of the braking mechanism 46, 48 and 50.

80 The ram 14 has a vertical groove 60 extending its entire length, this groove having flat parallel sides, and in the upper end of the standard 12 is a slot 61 of the same width as said groove 60.

85 On the opposite sides of said slot, ears 62 extend outwardly from said standard 12, the space between the upper portions of said ears 62 being covered by a plate 63 held in position by the pins 64, 65 extending through said ears.

90 The upper pin 64 has pivotally mounted thereon the depending key 66 of the same width as the groove 60 and the lower end of said key 66 is provided with a trigger 67 extending outwardly beneath said closing plate and by which the key 66 may be removed from said groove 60 when it is desired to lower the ram 14.

95 A spring 68 is secured at one end to the closing plate 63 with its other end disposed in a recess in the key 66 and this spring retains the key 66 in the groove 60 under normal conditions.

100 If the key 66 is removed from the groove 60 to permit the lowering of the ram, the ram will lower as long as the operator holds the key in its outer position, but as soon as the key is released the spring 68 will force the key 66 inwardly and when the groove 60 comes opposite said key in the rotation of the ram 14 said key will enter the groove 60 and prevent any further rotation and lowering of the ram 14.

105 This simple device is of considerable importance for it is obvious that the operator must hold the key in its outermost position when the ram is to be lowered and no further lowering will occur after he releases said key and permits the spring 68 to function.

110 At one side of the groove 60 is a scale 69 115

which indicates the height the load has been raised which is of great advantage, particularly where a load is being raised on a plurality of jacks operating at the same time and it is necessary to keep the load level during the raising operation.

The nut 16 is made at its upper end of smaller diameter than at its lower end thereby forming an annular space 70 for lubricant and from the bottom of this space 70 extend inclined passages 71 to the top of the nut and to a point near the bottom of the nut, all as shown in Fig. 1.

One of the screws 72 for securing the enlarged head 15 to the top of the ram 14 is removable to permit the insertion of a heavy oil into the chamber 73 within the ram 14 and this oil will flow through the upper inclined passages 71 to the annular space 70 from which it will flow through the lower inclined passages onto the threads of the screw 17.

By this means the threads of the nut 16 will be kept thoroughly lubricated at all times, a new supply of oil being inserted into the chamber 73 each day.

The inner end of the driving shaft 20 has a reduced end 74 extending into a ball bearing 75 mounted in a recess in one face of a member 76 depending from a pin 77 extending transversely of the extension 22.

The pin 76 is prevented from rotating in its bearing by a small key 78 but permits a swinging movement of the depending member 76 about the axis of said pin.

This construction is of great advantage as heretofore the weight applied to the end of the lifting lever when raising a load had a tendency to separate the two bevel gears 18, 19. This separation of the gears caused a binding effect between the teeth of the gears and also on the bearing for the driving shaft. The result was that the teeth could not get an even bearing on the pitch circle as all the strain was forced to the heel of the tooth. Consequently, the gears worked continually out of line and caused a binding which greatly increased the friction when working under a load.

By providing a ball bearing for the inner end of the driving shaft the gears are always in proper position relatively to each other and there is absolutely no binding or cramping effect as the teeth always get an even bearing on the pitch circle.

This reduces the friction and greatly increases the efficiency of the entire jack.

By removing the closure 79 in the extension 22 the worm 28 may be readily lubricated and by removing the closure 80 oil may be admitted to the interior of the bushing 60 forming the bearing 23 for the driving shaft 20.

The driving shaft 20 extends beyond the outer end of the bearing 23 and on a flat sided

portion 81 thereof is mounted the ratchet 82 while a reduced portion 83 thereof extends through a bearing in one wall of the casing 21 and has a transverse pin 84 therein to retain said casing 21 in position.

The opposite wall of the casing 21 has an opening therein large enough to admit the ratchet 82 into the interior chamber of the casing.

This opening is closed, when the casing 21 is positioned on the shaft 20 by a collar 85 surrounding said shaft.

Above the ratchet 82 the casing 21 has mounted therein an oscillating pin 86 with a head 87 at one end and a winged turning member 88 secured to its opposite end.

Keyed to the pin 86 within the casing chamber is a double ended pawl 89, each end of which is provided with a plurality of teeth 90 in a curved plane and either set adapted to engage the ratchet teeth.

At the upper end of the casing 21 is a boss 91 with a cylindrical opening 92 extending therethrough to the casing chamber.

A closure 93 is threaded to the outer end of the opening 92 and in this opening is disposed a ball 95 backed by a spring 94 tending to force the ball 95 downwardly against one wall of the pawl 89.

The pawl 89 has two walls perpendicular to each other and in one wall is a V-shaped groove 96 into which a portion of the ball 95 is adapted to extend and lock the pawl in adjusted position with one set of teeth 90 in engagement with the teeth of the ratchet.

This groove 96 is slightly at one side of the plane extending through the axes of the shaft 20 and the opening 92, as indicated in Fig. 8 of the drawings.

As a consequence the ball 95 bears on only one wall of the groove 96 and holds the pawl teeth and ratchet teeth in engagement during the lifting operation.

Extending from a side wall of the casing 21 is an inclined extension 97 having a socket 98 therein to receive the tapered portion 99 of the handle 100.

This tapered portion 99 of the handle 100 has extending inwardly from its end a groove 101 with a flaring mouth the inner end of said groove being curved around the periphery of the tapered portion 99 as indicated at 102.

Threaded to the extension 97 is a member 103 provided with ball shaped end 104 which extends into the socket 98 and is adapted to enter the groove 101 when the tapered portion of the handle is inserted into the socket.

By constructing this actuating mechanism in the manner shown and described, the moving parts, namely the pawl and ratchet, are enclosed within the casing 21 and kept free from dirt.

The lifting pawl 89 has a two point contact, one for raising the ram by means of the han-

dle 100 and the other for either raising or lowering the ram by manipulating the casing 21 without the handle or lever 100.

When this casing is to be actuated by hand 5 the brake levers 50 must be separated and the operator moves the casing 21 about the axis of the shaft 20 by means of the side projection 105 provided for this purpose.

This operation by hand can only be accomplished when there is no load upon the ram. 10

As soon as the operator releases the lifting member 21 the lifting pawl will immediately and automatically return to its neutral position.

15 This is of considerable advantage for as thus constructed and operated there is no chance for the operator to use the lifting lever in lowering the load and thus cause serious damage.

20 Moreover, there is no opportunity for the operator to make a mistake in lifting a load for there is only one position in which the lifting pawl will operate and that is in the lifting position.

25 When there is no load on the ram 14 it may be lowered more quickly than by the actuation of the lever socket by hand.

This is accomplished by withdrawing the key 66 from the groove 60 and turning the 30 ram by hand.

It is often desired to leave the load on the ram in raised position for an indefinite period and provision is therefore made to meet this condition.

35 This is accomplished by means of the screw 106 threaded in the member 30 and having a winged head 107 on the outer end and a head 108 on its inner end.

40 This screw radiates from the worm 39* meshing with worm gear 34 and when the head 108 is moved into a position against the threads of the worm 39*, this worm is locked from rotating and there can be no lowering until the head is again disengaged from the 45 worm.

It is obvious that when thus locked the operator does not depend upon springs to hold the load. This is of great advantage as 50 springs are not always safe, especially when workmen are under the load. This safety feature is of considerable importance.

The standard 12 is threaded to the upwardly extending projection 11 of the base 10 and is prevented from turning thereon 55 when assembled by the screw 12* extending through the lower end of the standard into said projection 11, as indicated in Fig. 1.

The lower end of the ram 14 has at its lower end a shoulder 14* adapted to coact with a 60 shoulder 13* at the upper end of the standard to limit the upward movement of the ram 14.

The screw 17 has a left hand thread and the lifting of the load is accomplished by bearing down on the lever 100.

65 The pawl 89 and ratchet 82 are wholly en-

closed in the casing 21 and the chamber therein is packed with grease which keeps the operating devices always in working condition.

The collar 85 on the shaft 20 is retained in the opening in the casing 21 by means of the screw 85*, the thread of which is partly in the wall of the casing and partly in the periphery of said collar.

In addition to the notch 96, the pawl 89 has another notch 96* therein midway of the 75 two sets of teeth 90 and when the pawl 89 is moved into a position with the notch 96* alined with the opening 92, the ball 95 will enter the notch 96* and retain said pawl in a neutral position with neither set of teeth 90 80 in engagement with the ratchet 82.

When in this position the ram cannot be raised or lowered by the device 21.

When it is desired to lower by hand with no load upon the ram the turning device 88 is turned clockwise to bring the right hand set of teeth 90 (see Fig. 8) into engagement with the ratchet teeth and then by holding the turning member 88 in this position the device 21 may be moved about the axis of the shaft 90 20 in either direction to raise or lower the ram.

As soon as the operator releases the turning member 88 the pawl 89 will return to its neutral position automatically.

The head 108 on the inner end of the screw 106 is of soft metal and is adapted to be jammed against the thread of the worm 39* so that it cannot be rotated.

The brake disk 49 rotates in the direction of the arrow on Fig. 6 and in the rotation of said disk the bearing plates 48 will be moved outwardly about their pivots by centrifugal force.

When thus moved outwardly the plates 48 will be brought into frictional engagement with the arms 50 and the speed of lowering may be regulated.

The bearing plates 48 have elongated slots 110 in their outer ends through each of which extends a pin 111 projecting upwardly from the disk 49.

These pins 111 limit the outward movement of the bearing plates 110, thereby making it possible to separate the arms 50 to such an extent that they will be wholly separated from said plates 48 and remove all frictional contact.

When the contact is thus removed, the ram may be lowered more rapidly under a light 120 load than would be possible if the plates 48 were in frictional contact with the arms 50.

Having thus described my invention, I claim:

1. In a lifting jack provided with a steep 125 pitch screw, a supporting casing having an elongated vertical opening therein with flat parallel sides and projecting ears, and a vertically movable ram in said casing having a peripheral slot with flat parallel sides extend-

ing lengthwise thereof; a closing plate interposed between said ears; a locking lever pivoted at its upper end to said ears and provided at its lower end with an actuating finger extending outwardly beneath said closing plate; and a spring between said closing plate and locking lever adapted to force said lever inwardly.

2. In a lifting jack provided with a steep pitch screw, a supporting casing having an elongated vertical opening therein with flat parallel sides and projecting ears; a vertically movable ram in said casing having a peripheral slot with flat parallel sides extending lengthwise thereof; a closing plate interposed between said ears; a locking lever pivoted at its upper end to said ears and provided at its lower end with an actuating finger extending outwardly beneath said closing plate; and a spring between said closing plate and locking lever, said spring being secured at one end to said closing plate and the other end disposed in a depression in the locking lever and adapted to force said lever inwardly.

3. In a lifting jack provided with a steep pitch rotatable screw, a supporting casing therefor, and a vertically movable ram; a nut fixedly secured in the lower end of the ram and coacting with said screw, said nut having passages extending to the top thereof through which lubricant may pass to the threads of said screw.

4. In a lifting jack provided with a steep pitch rotatable screw, a supporting casing therefor, and a vertically movable ram; a nut fixedly secured in the lower end of the ram and coacting with said screw, said nut having its upper end reduced in diameter providing an annular space for lubricant and having inclined passages extending to the top thereof and to a point near its bottom whereby lubricant may pass to the screw threads.

5. In a lifting jack provided with a steep pitch rotatable screw, a casing therefor, and a vertically movable rim; a driving shaft rotatable in a bearing in said casing and having a reduced cylindrical inner end; intermeshing gears on the lower end of the screw and inner end of said shaft; and a bearing for said inner end disposed above the screw gear and out of the path of said ram.

6. In a lifting jack provided with a steep pitch rotatable screw, a casing therefor, and a vertically movable ram; a driving shaft rotatable in a bearing in said casing and having a reduced cylindrical inner end; intermeshing gears on the lower end of the screw and inner end of said shaft; a vertical member within said casing disposed above the screw gear and out of the path of said ram; and a bearing removably mounted in said member for said inner end.

7. In a lifting jack provided with a steep pitch rotatable screw, a casing therefor, and a

vertically movable ram; a driving shaft rotatable in a bearing in said casing and having a reduced cylindrical inner end; a horizontal pin supported by said casing; a member depending therefrom; and a bearing for said inner end formed in the lower end of said member.

8. In a lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm above said worm gear and meshing therewith; and automatic brake mechanism surrounding one end of said worm and coacting therewith for retarding the lowering of said ram.

9. In a lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm meshing with said worm gear and meshing therewith; a removable member secured to said casing; and brake mechanism for regulating the lowering of the ram mounted on and movable with said removable member; said brake mechanism being normally connected to one end of said worm, but detachable therefrom.

10. In a lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm meshing with said worm gear; a removable member secured to said casing; and brake mechanism mounted on said removable member and normally coacting with and having a bearing for one end of said worm, said brake mechanism being adapted to regulate the lowering of the ram.

11. In a lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm meshing with said worm gear; a removable member secured to said casing in two sections bolted together; and brake mechanism mounted on the lower section of said removable member and normally coacting with said worm, said brake mechanism being covered by the upper section and adapted to regulate the lowering of the ram.

12. In a lifting jack provided with a steep pitch rotatable screw, a supporting casing therefor, and a vertically movable ram; a

- bevel gear secured to the lower end of said screw; a driving shaft having a bevel gear meshing with the screw gear; a worm gear on and rotatable with said shaft; a worm meshing with said worm gear; a removable member secured to said casing in two sections bolted together; brake mechanism mounted on said removable member and normally co-acting with said worm, said brake mechanism being adapted to regulate the lowering of the ram and including a cam shaft extending through the upper section; a cam actuating lever above said upper section secured to said cam shaft.
13. In a lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm meshing with said worm gear; a removable member secured to said casing in two sections bolted together; brake mechanism mounted on the lower section of said removable member and normally coacting with one end of said worm, said brake mechanism being adapted to regulate the lowering of the ram and including a cam shaft extending through the upper section; a cam actuating lever above said upper section secured to said shaft; a cam on the lower end of said cam shaft; brake arms on the opposite sides of said cam; and expansion springs for retaining said arms in contact with said cam.
14. In a lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm meshing therewith; brake mechanism coacting with said worm for retarding the lowering of said ram and including a second worm; and means coacting with the thread of said second worm and positively preventing the rotation thereof.
15. In a lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm meshing therewith; mechanism coacting with said worm and including a second worm; and a member adjustable endwise having a head at its inner end adapted to coact with the thread of said second worm to prevent its rotation.
16. In a lifting jack provided with a steep pitch rotatable screw, a supporting casing therefor, and a vertically movable ram; a bevel gear secured to the lower end of said screw; a driving shaft having a bevel gear meshing with the screw gear; a worm gear on and rotatable with said shaft; a worm meshing therewith; a brake mechanism coacting with said worm, said brake mechanism being adapted to regulate the lowering of the ram and including a second worm; and a screw threaded to said casing radiating from said second worm and provided with a head adapted to coact with the thread of said second worm to positively prevent its rotation.
17. In a lifting jack provided with a steep pitch rotatable screw, a supporting casing therefor, and a vertically movable ram; a bevel gear secured to the lower end of said screw; a driving shaft having a bevel gear meshing with the screw gear; a brake mechanism including a plurality of movable members; and a safety device for positively locking the movable members from rotation adapted to be moved into engagement with one of said movable members.
18. In a lifting jack provided with a steep pitch rotatable screw, a casing therefor; and a vertically movable ram; a driving shaft rotatable in a bearing in said casing and having a reduced cylindrical inner end; and a member provided with a bearing for said inner end and adapted to be removably positioned within said casing.
19. In a lifting jack provided with a steep pitch rotatable screw, a casing therefor; and a vertically movable ram; a driving shaft rotatable in a bearing in said casing and having a reduced cylindrical inner end; a swing member within said casing; and an anti-friction bearing for said inner end mounted in said member.
20. A lifting jack comprising a casing; a rotatable lifting screw and a driving shaft mounted in said casing with their axes disposed at an angle to each other and in a common vertical plane, a driving connection between said shaft and screw; a vertically movable ram on said screw; and a bearing above the screw driving connection and in which the inner end of said shaft is journaled, said bearing being outside the boundary of said ram.
21. In a lifting jack, the combination of a lifting screw; a driving shaft therefor; an operating lever for said shaft; and means including a casing mounted on said driving shaft for automatically establishing an operative connection between said lever and said shaft upon movement of the lever in one direction only, said means also including a movable device adapted to be retained by hand in adjusted position whereby the casing may be temporarily connected to the shaft upon movement of the casing in the opposite direction.
- Signed by me at 746 Old South Bldg., Boston, Mass., this 27th day of November, 1926.

FRANK L. GORMLEY.
